UNITED STATES PATENT OFFICE.

JOHN SOLTYS, OF DETROIT, MICHIGAN.

ARTICLE SUPPORT.

Application filed January 18, 1921, Serial No. 438,199. Renewed April 16, 1923.

To all whom it may concern:

Be it known that I, JOHN SOLTYS, a citizen of Poland, residing at Detroit, in the county of Wayne and State of Michigan, have invented new and useful Improvements in Article Supports, of which the following is a specification.

This invention has for its object the provision of a truck designed to support and 10 convey blow pipes for blast furnaces, the construction being such that the pipe can be conveniently handled with a minimum amount of effort, and the pipe conveniently turned to any angle with respect to the truck 15 upon which it is mounted.

The nature and advantages of the invention will be better understood when the following detail description is read in connection with the accompanying drawings, the 20 invention residing in the combination, construction and arrangement of parts as claimed.

In the drawings forming part of this application, like numerals of reference indicate the similar parts in the several views and wherein:—

Figure 1 is a side elevation of the invention showing the manner of positioning the support to receive the article to be supported thereby.

Figure 2 is a side elevation of the invention, showing the position of the support when the article has been positioned thereon.

Figure 3 is an end elevation of the support, showing the article positioned thereon.

Figure 4 is an enlarged sectional view through the two-part clamp showing the manner of associating the clamp with the support proper.

Figure 5 is a fragmentary plan view, showing the article engaging yoke and its association with the support proper.

Figure 6 is a fragmentary view of a modified form.

In a form of the invention the truck embodies a wheeled frame which comprises a pair of divergently disposed limbs 10 and 11 respectively which are bent together from an appropriate point in their length to provide an obliquely disposed portion 12 and a loop 13. A lifting arm including the respective branches 14 and 15 is associated with the frame, the branch 14 being secured to the obliquely disposed portion 12 of the frame and based thereon the loop 13. The

portion 14 is terminally offset as at 16 and has swiveled thereon a yoke 17 for a purpose to be hereinafter described.

Rotatably associated with the offset terminal 16 is a link 18 which has pivoted thereon a second arm 19 which is arranged above the branch 15 of the aforementioned arm. The arm 19 is bent at an appropriate point in its length to provide a loop 20 which receives the pivot 21 and associates the arm with the link 18, the arm having a terminal portion providing an eye 22 in which is swivelly mounted a sectional link 24, the sections of which are held together by means of a fastening element 25. The divergent limbs of the frame have their lower ends extended laterally and journaled thereon are wheels 26.

In practice, the blow pipe which is indicated at 27 has associated therewith a link 28 through which a hook 29 is carried by a chain 30 to which it is adapted to be connected. The chain is utilized to extend the pipe on one end, the chain being connected to the lifting arm 14 as shown. When the parts are positioned in the manner shown in Figure 2 the pipe is arranged within the yoke 17 and the sectional link or band 24, after which the truck can be righted so that the pipe is supported in a horizontal position. The maximum weight of the pipe is supported by the arm 14 while a portion of the weight is also supported by the arm 19. With the pipe arranged in horizontal position upon the truck the latter can be easily moved over the surface, and a pipe turned to any angle or position with respect to the wheeled frame through the instrumentality of the arm 19. This is permitted by the offset extremity 15 of the arm 14 by means of the link.

In a modified form of the invention, the divergent limbs 30' of the wheeled frame has swiveled on the extremities thereof are 100 the casters 32, the invention in this form being the same as the element above described.

While it is believed that from the foregoing description the nature and advantages of the invention will be readily apparent, I desire to have it understood that I do not limit myself to what is herein shown and described, and that such changes may be resorted to when desired as fall within the scope of what is claimed.

What I claim is:—

1. An article support of the character de-

scribed comprising a wheeled frame, a stationary arm associated with said frame and having angularly disposed branches, a yoke swiveled on one of said branches, a second arm including angularly disposed branches for connecting the first mentioned arm for movement thereto, and a sectional band carried on the branch of the second mentioned arm and arranged in juxtaposition 10 within said yoke for the purpose specified.

2. An article support of the character described comprising a wheeled frame, a

stationary arm including angularly disposed branches secured to said frame, a yoke swiveled on one end of said arm, a second arm including angularly disposed branches associated with the first mentioned arm for both lateral and vertical movements, and a sectional band carried by the second mentioned arm and arranged in juxtaposition to said 15 yoke for the purpose specified.

In testimony whereof I affix my signature.

JOHN SOLTYS.
